[57] CLAIM

The ornamental design for a ground inserted umbrella support, as shown and described.

DESCRIPTION

FIG. 1 is a front elevational view of a ground inserted umbrella support showing my new design;

FIG. 2 is a rear elevational view thereof;

FIG. 3 is a left elevational view with the right side being a mirror image thereof;

FIG. 4 is a top plan view thereof;

FIG. 5 is a bottom plan view thereof; and,

FIG. 6 is a front elevational view with an umbrella shown in broken lines for illustrative purposes only and forms no part of the claimed design.
